R. FABIG.
INKING DEVICE FOR TYPE PRINTING APPARATUS.
APPLICATION FILED JULY 8, 1920.

Patented Nov. 7, 1922.

FIG.1.

FIG.2.

FIG.3.

Inventor:

Robert Fabig

By Lawrence Sawyer

Attorney.

UNITED STATES PATENT OFFICE.

ROBERT FABIG, OF NEURUPPIN, GERMANY, ASSIGNOR TO RINDERT SCHEFFER, OF AMSTERDAM, NETHERLANDS.

INKING DEVICE FOR TYPE PRINTING APPARATUS.

Application filed July 8, 1920. Serial No. 394,842.

(GRANTED UNDER THE PROVISIONS OF THE ACT OF MARCH 3, 1921, 41 STAT. L., 1313.)

To all whom it may concern:

Be it known that I, ROBERT FABIG, a citizen of the Free State of Prussia, in the German Republic, residing at Neuruppin, 5 in the Free State of Prussia, Germany, have invented Improvements in Inking Devices for Type Printing Apparatus (for which I have filed application in Germany Apr. 12, 1918, Patent No. 309,848); and I do hereby 10 declare the following to be a full, clear, and exact description of the same.

The invention relates to a device for inking the types of such type printing apparatus, for instance typewriting machines, in 15 which no ribbons are used but the types inked by direct contact with an ink roll. According to the simplest modification devices of such kind are so constructed and used that the printing apparatus is provided 20 with a casing for the ink roll, in which said roll supplied with ink is arranged. When the ink is consumed the roll is removed and replaced by another inkable roll.

These apparatus had the disadvantage 25 that the troublesome and dirty work of taking out the used roll and replacing the new roll had to be carried out relatively often.

Endeavours have been made to obtain a 30 longer duration of the ink roll by positively pressing the latter against an ink cushion after each contact with a type. As however always the same portion of the cushion is met by the type this method is of little success only. This method has moreover the 35 disadvantage that only a small part of the inked surface of the ink cushion is used. To supply the ink cushion with fresh ink is however just as troublesome and dirty as 40 the change of the ink roll of the older construction mentioned above which is much more simple.

According to my new invention the disadvantages of the known constructions are 45 obviated by the use of means which allow a much more simple and much better use than is the case when employing the well known devices mentioned above. The use of the present device makes soiling of the hands 50 nearly impossible.

A feature of this invention is the provision of a wick arranged and guided in the manner of a lamp wick and adapted to sup-

ply ink to the ink roll when the latter is pressed into contact with the wick.

The arrangement may of course be such that the type is brought into contact with the wick directly, so that the type itself is provided with ink from the wick. In most cases however, this arrangement is not advantageous since the type impressions are not as uniform and strong as when the inking roller is provided.

When after extended use of the wick and the ink supplied to the latter is consumed, 65 the wick is advanced by a feeding device and the consumed portion of the wick may be cut away by scissors. In order to further extend the life of the wick, the arrangement may be such that the wick is immersed in a 70 reservoir filled with the liquid ink.

The invention is shown in the drawings by way of example.

Fig. 1 is a front view partially in section of the new device,

Fig. 2 is a side elevation, the ink roll being omitted,

Fig. 3 is a section taken on the line *a—b* of Fig. 1,

Fig. 4 is a section taken on the line *c—d* 80 of Fig. 3 showing the position in which the ink roll is supplied with ink by the wick.

According to the construction shown in Figs. 1 and 3 a roll 2 consisting of wood, caoutchouc or the like is placed upon a pin 85 1 and this roll carries a cylindrical ink cushion 3. A lever 4, carrying the pin 1, is mounted upon a stud 5 which is secured to the frame of the device by means of a thread 6. The latter carries a tubular 90 sleeve 8 in which is arranged a cylindrical wick 9. The wick 9 is moved by the turning of a disc 10 and its end to be fed for later use is immersed into a reservoir filled with ink which is however not shown in the 95 drawing. The feeding device of the wick is well known from the oil lamps and the like and a shaft 11 is provided which carries a toothed wheel. The latter projects through a slot 13 into the sleeve 8 and engages the wick arranged in said sleeve.

When the type 14 is moved to the printing position it first impinges upon the roll shaped ink cushion 3 and is supplied with ink from the latter. Then the type drives 105 the cushion in front of it until it escapes

laterally freeing the way for the type to contact against the paper to be printed. The lateral movement of the ink roll is effected by turning of the lever 4 so that the 5 cushion 3 is by way of the dotted lines shown in Fig. 1 advanced to the sleeve 8 until it comes into contact with the wick 9 which is at this portion uncovered by a slot 15 of the sleeve 8.

10 During this time the type 14 has been moved into contact with the paper upon the platen and effected the printing, whereupon it is returned to the position of rest. The roll 2 also returns under the action of a 15 coiled spring 16. One end of the spring is arranged around the sleeve 18 and is extended to a nut 16 firmly secured upon the thread 6 of the stud 5. A second spring 16¹ forms a limit stop for the ink roll 3 and this 20 stop may easily be removed sideways. The arm 19 carrying the holder for the ink roll is soldered to the sleeve 8.

Having now described and ascertained the nature of my invention and the manner in 25 which the same is to be performed I now declare what I claim and desire to secure by Letters Patent of the United States:

In a machine for printing from types the combination of an ink saturated wick, a 30 tubular open ended sleeve enclosing and guiding said wick and having a longitudinal slot, means for feeding said wick to bring a fresh portion thereof into the said slot, a 35 rotatable and oscillatory inking roller in parallel position with regard to the wick containing sleeve, and types, the inking roller upon being struck by a type being oscillated to come in contact with the wick at said slot to receive ink from the wick.

40 2. In a machine for printing from type, the combination of an ink saturated wick; a casing for guiding said wick; an inking roller; a pin on which said roller is rotatably mounted; a rotatably mounted member 45 on which said pin is mounted; a spiral

spring on said member; and types, said member carrying the inking roller being rotated against the action of said spring when a type strikes against said inking roller to move the inking roller into contact with the wick to receive ink therefrom, the spring acting to return the member with the roller to normal position. 50

3. In a machine for printing from type, the combination of an ink saturated wick; 55 a casing for guiding said wick; means for feeding the wick; an inking roller; a pin on which said roller is rotatably mounted; a rotatably mounted member on which said pin is mounted; a spiral spring on said member; and types, said member carrying the inking roller being rotated against the action of said spring when a type strikes 60 against said inking roller to move the inking roller into contact with the wick to receive ink therefrom, the spring acting to return the member with the roller to normal position. 65

4. In a machine for printing from type, the combination of an ink saturated wick; 70 a casing for guiding said wick; an opening at one end of said casing; means for feeding said wick to bring a fresh portion thereof to said opening; an inking roller; a pin on which said roller is rotatably mounted; 75 a rotatably mounted member on which said pin is mounted; a spiral spring on said member; and types, said member carrying the inking roller being rotated against the action of said spring, when a type strikes 80 against said inking roller, to move said roller through said opening into contact with the wick to receive ink therefrom. 85

In testimony whereof, I have signed my name to this specification in the presence of two subscribing witnesses.

ROBERT FABIG.
